US0D1073228S

(12) **United States Design Patent** (10) **Patent No.:** **US D1,073,228 S**
(45) **Date of Patent:** **** Apr. 29, 2025**

(54) **CONNECTION ELEMENT FOR VACUUM CLEANER BAG**

(71) Applicant: **Dongguan Guangsheng Trading Co., Ltd.**, Dongguan (CN)

(72) Inventor: **Guangsheng Cui**, Dongguan (CN)

(73) Assignee: **Dongguan Guangsheng Trading Co., Ltd.**, Dongguan (CN)

(**) Term: **15 Years**

(21) Appl. No.: **29/968,740**

(22) Filed: **Oct. 18, 2024**

(51) LOC (15) Cl. **15-05**

(52) U.S. Cl.

USPC **D32/31**

(58) **Field of Classification Search**

USPC D8/382, 394, 396, 499; D15/147; D32/25, 30, 31, 32, 39

(57) **CLAIM**

The ornamental design for a connection element for vacuum cleaner bag, as shown and described.

DESCRIPTION

FIG. 1 is a front perspective view of a connection element for vacuum cleaner bag, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is the connection element for vacuum cleaner bag in a state.

The broken lines in the drawings illustrate the portions of the connection element for vacuum cleaner bag, which form no part of the claimed design.

1 Claim, 9 Drawing Sheets
